UNITED STATES PATENT OFFICE

2,435,226

DISINTEGRATOR HOUSING WITH DISH-SHAPED SIDES

Clarence W. Lanter, Du Page County, Ill., assignor to Birtman Electric Company, a corporation of Illinois

Application January 17, 1944, Serial No. 518,492

2 Claims. (Cl. 241—86)

1

This invention relates to a disintegrator or hammer mill and more particularly to a disintegrator intended for farm or large scale use.

The invention is illustrated in the drawings in which Figure 1 is a side elevation of the disintegrator; Figure 2 is a similar view from the opposite side of the disintegrator; Figure 3 is a plan view; Figure 4 is a sectional plan taken along the line 4—4 in Figure 6; Figure 5 is a sectional elevation taken along the line 5—5 in Figure 6; Figure 6 is a sectional elevation of the disintegrator chamber; Figure 7 is a side elevation of a modified form of the disintegrator with portions broken away; and Figure 8 is a view, partially in section, taken along the line 8—8 of Figure 7.

The disintegrator comprises a disintegrator rotor assembly 10 which is mounted upon a hexagonal rotor shaft 11 journalled in the bearings 12 and 13. The rotor consists of blades 15 directly carried by the shaft 11 and spaced from each other in suitable fashion. The blades carry the hammers 16 which are secured to the blades by the pins 17 and 18 which extend through a plurality of the blades. The hammers are preferably double-ended, being provided with the striking surfaces 19 and 20, each of which is broken up into a plurality of stepped faces 21. It is preferred to employ eight blades, each of which carries two hammers, one at each end. It is also preferred to mount four blades parallel upon the shaft and the other four blades at a 90° angle therefrom, and the hammers carried by the blades are so spaced that, as the disintegrator rotates, the succeeding hammer faces cover the peripheral area not covered by the preceding set. In other words, the hammer blades are so staggered that two successive groups of hammers cover the entire peripheral striking area.

The structure and arrangement of the hammers is described more fully and is claimed in my co-pending application Serial No. 518,490, filed January 17, 1944.

The hammers are rotated in the rotor chamber 25 formed by the split housing 26. This housing consists of an upper housing 27 which includes the feed section 28; and a base housing 29. The upper housing 27 and the base housing 29 are pivotally connected at 30, and any suitable locking means are provided, such as the latch 31.

Within the disintegrator housing is the grinding screen 25 having a section 35a in the upper housing and a section 35b in the lower housing and which, for at least approximately half of the circumference of the circle formed by the hammer, is concentric with them. It is desirable that the screen 35 be readily replaceable, and further that the means for mounting it within the chamber be firm and yet not interfere with the passage of air or solid particles through the screen. This

2

has been accomplished in the present device, by the formation of complementary integral grooves 36, 37, 38 and 39 in the upper and base housings. It is preferred that the housing be made of sheet metal of suitable thickness, into which the grooves are formed by any suitable metal-forming operation, preferably by stamping. It will be observed that upon opening of the housing by release of the latch 31 and raising of the upper housing, the screen 35 is withdrawn automatically from the grooves 38 and 39 and may then be manually withdrawn from the lower grooves 36 and 37.

The grooves, in addition to providing a support for the screen which is effective against either inwardly or outwardly directed forces, do not occupy any part of the chamber which would otherwise be useful for the passage of air or solid material and, therefore, do not set up eddy currents or tend to cause blocking of the screen. Furthermore, these substantially circular grooves considerably reinforce the strength of the housing and permit the use of sheet metal of a lower gauge.

The screen terminates on the inside at the breaker bars 40. The location of the breaker bar 25 in the rear of the rotor housing is a departure from customary practice which is of value because of the fact that the breaker bars tend to cause formation of fine powder to an objectionable degree where they are placed, as is usual, at a point in the housing anterior to the screen. In the present device a great deal of material will never impinge upon the crusher bars but will be carried in a stream between the hammers and the screen or will pass through the latter without reaching the crusher bars. The crusher bar faces are at an angle which will throw the material striking them back into the hammers. This means that practically no material should strike the face at a right angle or greater.

40 Material to be ground or crushed is introduced to the disintegrator chamber from the trough 41 which is connected to the feed section or opening 28 through the adjustable gate mechanism 42. This gate mechanism is of customary type and need not be described further.

45 The bottom section of the housing compartment is provided with the cantboard 45 which extends transversely across the housing and directs the flow of ground material which is passed through 50 the screen down the cantboard and toward the exhaust opening 46 which is shown in Figure 2. The cantboard 45 may be designated as a front cantboard. Behind the exhaust opening 46 is the rear cantboard 47. The positioning of the exhaust opening 46 together with the slope of the rear cantboard 47 is of considerable importance. It is preferred that this slope shall be not less than 60°, in order that there shall be no tendency for grain to pile up on the cantboard and either clog 55 the apparatus or break loose in considerable quan-

tities to produce an irregular supply of the material which causes clogging. Furthermore the positioning of the opening 46 toward the rear of the chamber tends to produce less drag upon the fan.

Suction is applied to the disintegrator chamber by means of the fan 50 having the blades 51 and mounted upon an extension of the shaft 11. The fan is held within the fan housing 52 which communicates through the passage 53 with the outlet 46 and the disintegrator chamber. Powdered material is drawn through this series of passageways through the fan and out through the customary exhaust 54 to any suitable loading device, not shown.

As shown in Figures 7 and 8, the outlet or exhaust 46a is provided in the rear edge wall 80 of the disintegrator. In this case the exhaust 54a is carried up at an angle to the fan chamber.

It will be noted that throughout, the structure housing has been built up of sheet metal material arranged without sharp corners and shaped to provide the utmost in strength. As a result of the form of the sheet metal, the weight of the hammer mill has been greatly reduced so that a mill which formerly weighed around 550 lbs. can be produced with equal or greater strength and capacity and weighing in the neighborhood of 310 lbs.

These results are accomplished by the use of stamped material shaped and formed to put the material under tension so far as possible and by the use of a minimum number of auxiliary fastening devices. It is also due to the light weight of the disintegrator blades 15 which have been made lighter and stronger by the formation of bearing and other openings by means of an extrusion process. For example, the hexagonal opening 66 which fits the hexagonal shaft 11 is formed by extruding the metal formerly occupying the opening to form the flange 62 which encloses the shaft and provides an extra bearing surface as well as reinforcing the blades against lateral movement, and providing the spacing means. The same is true of the flanges 63 and 64 which are formed from the openings which admit the pins 17 and 18.

The side walls 65 and 66 of the disintegrator housing are disked to provide extra strength as well as a more suitable conformation for the disintegrator housing; and this shaping, particularly in combination with the displacement to form the grooves 36, 37, 38 and 39, permits the wall of the housing to be made of particularly thin material.

It will likewise be observed that the top corners 67 and 68 as well as the top wall 69 are stamped in rounded form to provide extra strength.

The fan housing is particularly characterized by the absence of the usual external bolts holding together the side walls 70 and 71. The use of these external bolts requires an upstanding flange and a very considerable weight of metal which is avoided by the present structure. In this structure the edge wall 72 of the fan housing is provided with an inturned flange 73 to which are welded, at suitable intervals, lugs 74. Usually from six to eight of these lugs are sufficient. The side wall 71 is provided with a horizontal flange 75 and with openings corresponding to the lugs 74 so that, on assembly, the flanges 73 and 75 are closely fitted and the walls 71 and 72 are bolted together by suitable threaded nuts 76 on the lugs 74.

In my co-pending application Serial No. 518,491, filed January 17, 1944, there is set forth subject matter relating to the present invention.

The foregoing detailed description has been given for clearness of understanding only, and no unnecessary limitations should be understood therefrom.

What I claim as new and desire to secure by Letters Patent is:

1. In a disintegrator or hammer mill, a rotatable hammer blade, a disintegrator chamber defined by a housing about said blade, a unitary screen within said housing surrounding a major portion of the area of travel of the blade and concentric thereto for a part only of its length, said screen being so constructed and arranged that the screen has a greater radius of curvature at the beginning of the disintegrating zone but gradually diminishing until a constant radius is reached for approximately one-half the area of travel of said blade, an opening for introducing material to be ground into the chamber, an outlet opening for withdrawing ground material from a point near the bottom of the chamber, an imperforate cantboard sloping toward the plane of the outlet opening, and said disintegrator housing having dish-shaped sides with the concave surfaces thereof being toward said hammer blade.
2. In a disintegrator or hammer mill, a rotatable hammer blade, a disintegrator chamber defined by a housing about said blade, a screen within said housing surrounding a major portion of the area of travel of the blade and concentric thereto for a part only of its length, said screen being so constructed and arranged that the screen has a greater radius of curvature at the beginning of the disintegrating zone, but gradually diminishing until a constant radius is reached for approximately one-half the area of travel of said blade, an opening for introducing material to be ground into the chamber, and an outlet opening for withdrawing ground material from a point near the bottom of the chamber, said outlet opening being in the rear edge wall of the housing with said rear edge wall being beneath the feed opening and away from the direction of rotation of said hammer blade, and said disintegrator housing having dish-shaped sides with the concave surfaces thereof being toward said hammer blade.

CLARENCE W. LANTER.
